DESIGN FOR A WALL CLOCK

Gordon W. Florian, Bridgeport, Conn., assignor to
Casco Products Corporation, Bridgeport, Conn.,
a corporation of Connecticut

Application October 11, 1947, Serial No. 141,867

Term of patent 14 years

(CL. D42—7)

To all whom it may concern:

Be it known that I, Gordon W. Florian, a citizen of the United States, residing at Bridgeport, county of Fairfield, and State of Connecticut, have invented a new, original, and ornamental Design for a Wall Clock, of which the following is a specification, reference being had to the accompanying drawing, forming part thereof.

Figure 1 is a front view of a wall clock showing my new design.

Fig. 2 is a side view of the same; and

Fig. 3 is a bottom view of the same.

The essentials of my design for a wall clock are shown in full lines, the numerals shown in broken lines are merely representative of what

will appear within this space from time to time.

I claim:

The ornamental design for a wall clock, as shown and described.

GORDON W. FLORIAN.
